MATCH BOX

Filed Dec. 26, 1922

BY
J. F. YOUNG
ATTORNEY.

UNITED STATES PATENT OFFICE.

JESSE F. YOUNG, OF NORTHPOR, NEBRASKA.

MATCH BOX.

Application filed December 26, 1922. Serial No. 609,080.

To all whom it may concern:

Be it known that I, JESSE F. YOUNG, a citizen of the United States, residing at Northport, in the county of Morrill and State of Nebraska, have invented certain new and useful Improvements in Match Boxes, of which the following is a specification.

My invention relates to match boxes and its primary object is to provide a receptacle for storing matches, which forms a part of a can of the type at present commonly used for the sale of tobacco.

The receptacle may be formed integral with the can, or it may be made separate and attached either to the lid or at the bottom thereof.

Another object of my invention resides in providing a match receptacle of the above described character which has convenient means to deliver the matches singly and without the use of movable lids or other closing devices, and still another object is to provide a match receptacle for use in the above described manner which is made of a single piece of metal.

With the above and other objects in view, all of which will fully appear in the course of the following description, my invention resides in the constructions and arrangements of parts illustrated in the accompanying drawings in the various views of which like parts are similarly designated and in which—

Figure 1 represents in partially sectional elevation, a tobacco can having a match box fastened at the bottom end thereof;

Figure 2, a perspective view of the match box in an inverted position;

Figure 3, a transverse section along the line 3—3, Figure 1;

Figure 4, a similar section taken on the line 4—4, Figure 1;

Figure 5, an elevation of the upper portion of a tobacco can showing the match box connected to the hinged lid thereof;

Figure 6, a section taken on the line 6—6, Figure 5;

Figure 7, a section along the line 7—7, Figure 5;

Figure 8, an elevation of the tobacco can drawn to a reduced scale, with the match box forming an integral part thereof;

Figure 9, a section taken on the line 9—9, Figure 8; and

Figure 10, a section along the line 10—10, Figure 9.

Referring first to Figures 1 to 4 of the drawings, the reference character 5 designates a tobacco can of conventional construction provided at one end with a flanged lid 6 hinged as at 7.

The bottom 8 of the can is crimped to the body portion 9 of the same and forms a bead 10 at the end of the can opposite to that at which the lid is fastened, which in the preferred form of the invention, is employed to fasten the match box.

The box consists of an oblong shell 12 conforming in longitudinal section with the cross sectional contour of the tobacco can and having at its open top channeled flanges 13 adapted to slidingly embrace the opposite sides of the circumferential bead at the bottom of the can.

The ends of the shell are at the edge thereof, extended to provide prongs 14 which by entering the depression in the bottom end of the can as shown in Figure 1 aid in holding the box against accidental displacement.

The sides of the box are convergingly drawn together at the bottom thereof to form a narrow slot or mouth 15 through which the matches are discharged, and they are severed from the shell at the ends thereof by slits 16 to provide lips 17 of sufficient resiliency to permit of their spreading apart for the passage of a match when it is pulled downwardly through the mouth of the box.

In order to permit of the user taking hold of the matches in the container for the purpose of pulling them through the slot in the bottom of the same, the lips have opposite openings 18 through which the finger and thumb are inserted.

The sides of the container may be roughened as at 19 to provide a friction surface upon which the matches can be struck for the ignition of their inflammable tips.

In the form of my invention shown in Figures 5, 6 and 7, the container is proportioned at its open side to fit snugly over the lid of the can and it has at one of its longitudinal edges a plurality of curved prongs 20 adapted to enter into the openings formed in the side of the can to admit the hinge-knuckles of the lid. In this form of my invention, the match container moves with the lid and the matches are easiest withdrawn when the lid is in the open position.

In the construction illustrated in Figures 8, 9 and 10, the match box is formed by extending the wall of the tobacco box and the bottom of the latter is fastened in a bead 5 21 of said wall. The construction is illustrative of a convenient manner of forming the match container as an integral part of the tobacco can and it will be apparent that other methods may be resorted to within 10 the spirit of my invention.

The match container of the last described form has at one end an opening 22 normally closed by a slide 23, by means of which it can be supplied with matches.

15 Having thus described my improved match box in the best forms at present known to me, I desire it understood that variations in details of construction of the container and the means for fastening it 20 either removably or permanently to the

tobacco cans, may be availed of without departing from the scope of my invention as defined in the hereunto appended claim.

What I claim and desire to secure by Letters Patent is:

An attachment for tobacco boxes comprising a one piece receptacle open at its top for its connection with the box and having end members and side-members formed integrally of one piece of metal, the side-members curving inwardly at the bottom of the receptacle to form a slot for the withdrawal of matches from the receptacle and the end-members of the sides being slit to permit of their moving apart for the passage of a 35 match between them.

In testimony whereof I have affixed my signature.

JESSE F. YOUNG.
